UNITED STATES PATENT OFFICE.

DANIEL I. COWGILL, OF LEXINGTON, KENTUCKY

METALLIC RAILROAD-TIE.

1,260,336.

Specification of Letters Patented, Mar. 26, 1918.

Application filed May 8, 1916, Serial No. 26,879.

To all whom it may concern:

Be it known that I, DANIEL I. COWGILL, a citizen of the United States of America, residing at Lexington, in the county of Fayette and State of Kentucky, have invented certain new and useful Improvements in Metallic Railroad-Ties, of which the following is a specification, reference being had therein to the accompanying drawing.

10 This invention relates to metallic railroad ties and has for its object the production of a simple and efficient tie which may conveniently support a rail and hold the rail in such a position as to prevent the same from 15 being accidentally detached therefrom and also prevent the rails from spreading.

Another object of this invention is the production of an efficient railroad tie of metal construction which consists of a minimum number of parts.

20 With these and other objects in view this invention consists of certain novel combinations, constructions, and arrangements of parts as will be hereinafter fully described 25 and claimed.

In the accompanying drawings:

Figure 1 is a side elevation of the railroad tie.

Fig. 2 is a top plan view of the railroad 30 tie.

Fig. 3 is a section taken on line 3—3, of Fig. 1 looking in the direction of the arrow.

Fig. 4 is a section taken on line 4—4, of Fig. 2.

35 Fig. 5 is a section taken on line 5—5, of Fig. 2.

Fig. 6 is a bottom plan view of one end of the railroad tie.

Fig. 7 is a perspective view of the top of 40 one end of the tie.

Fig. 8 is an inverted perspective view of one of the rail retaining plates.

Fig. 9 is a perspective view of one of the closure plates adapted to be carried by the 45 side of one of the railroad ties.

Fig. 10 is an enlarged longitudinal section through the bottom of the tie showing the cleats formed upon the bottom face thereof.

By referring to the drawings it will be 50 seen that 1 designates the body of the tie which comprises a rectangular hollow structure, preferably being formed of metal. The body 1 is provided with a plurality of transversely extending cleats 2 upon the bottom 55 face thereof, preferably T-shape in cross section, which cleats are adapted to grip the

ballast of the roadbed and hold the body 1 of the tie against lateral movement with respect to the roadbed.

The body 1 is provided near each end with 60 an aperture 3 upon each side of the body, which apertures are closed by means of the pivotally mounted gates or closure plates 4. These closure plates 4 are adapted to normally close the openings 3 to prevent the 65 entrance of ballast or other foreign substance to the interior of the tie. By means of the apertures 3 it will be seen that access may be easily had to the interior of the body to facilitate the fastening of the rail retaining plates in engagement with the body as 70 will be hereinafter more fully described.

The body 1 of the tie is provided intermediate the ends thereof with the upwardly projecting or raised portion 5, the ends of 75 which raised portion 5 constitute shoulders 6 for abutting against the ends of the inner rail retaining plates 7.

Each rail retaining plate 7 comprises a flat body having a tapering rail engaging 80 lip 8 at one end. A plurality of spaced integral ribs 9 are formed upon the lower face of each rail retaining plate 7, and these ribs 9 are each provided with an inclined face 10 to facilitate the placing of the plate 7 in 85 its proper position upon the tie 1. A plurality of transversely extending sockets 11 are formed upon the upper face of the body 1 of the tie for the purpose of receiving the ribs 9 formed upon the lower face of the 90 rail retaining plate 7.

Each of the rails 12 is engaged upon the outer side thereof by means of a rail retaining plate 13. Each rail retaining plate 13 is provided with a plurality of ribs 14 similar to the ribs 9, which ribs fit in the sockets 15 formed upon the upper face of the tie 1.

The tie 1 is provided upon the under face of the top thereof with a plurality of reinforcing longitudinally extending ribs 16 100 formed near each end thereof and adapted to be formed directly under the rail seat 17 formed in the body 1 of the tie.

The rail retaining plates 7 and 13 are 105 firmly held in engagement with the tie by means of the vertically extending bolts 18, which bolts extend through the ribs 16, body 1 and through the respective plates 13 and 7. These bolts carry nuts 19 for the purpose of allowing the rail retaining plates 110 7 and 13 to be easily or readily detached from the body of the railroad tie.

It should be understood that the transversely extending cleats 2 may be formed integral with the body 1^a as indicated by the numeral 2^a in Fig. 1 without departing from the spirit of the invention. As clearly illustrated in Fig. 4 it will be seen that the top of the tie or body 1 is thickened as indicated by the numeral 20 just below the rail seat 17 to add additional strength to the tie 10 below the point where the rails are supported thereby.

It will be noted by referring to Figs. 4 and 7, that the openings 18' through which the bolts 18 project, extend through the body of the tie at points between the transversely extending sockets 11 and 15 of the tie body 1. Therefore, the bolts will have a broader reinforcing surface in passing through the tie body 1, and thus the bolts 20 will be held from bending and will retain the rail plates more easily. Furthermore, since the bolts do not project through the ribs of the rail plates, these ribs are not weakened, but being of solid construction, 25 without bolt openings will positively hold the rail plates in a set position. It should further be noted that the longitudinal ribs 16 formed upon the rail body 1, have bulged portions 16' so as to provide sufficient space 30 for the openings 18' through which the bolts extend. In this way the longitudinal ribs will reinforce the portions of the tie body 1 upon which the rails are supported and at the same time the ribs 16 are light and inexpensive in operation and construction, 35 while by being bulged at 16' the ribs will be held from splitting or tearing when the bolt

openings 18' are formed therethrough or while the bolts are in operation and project through the bolt openings 18'.

Having thus described the invention what is claimed as new is—

In a metallic railroad tie, the combination of a tie body, said body having transversely extending sockets formed in its upper surface, each socket being spaced at a distance from its adjacent sockets, thereby forming bearing surfaces between said sockets, elongated longitudinally extending spaced ribs formed integrally upon the under surface 50 of said tie body, said ribs being formed in planes crossing and below the planes of said sockets, whereby said body will be reinforced where the greatest strain is brought to bear thereon, said ribs having bulged portions 55 adjacent their ends, said bulged ends and said tie body having bolt openings projecting vertically therethrough, the upper ends of said bolt openings communicating with said bearing surfaces between said sockets, 60 tie plates having spaced ribs formed thereon, said plates having bolt openings formed therethrough between said ribs, said ribs fitting within said sockets, and bolts extending through said bolt openings, whereby said 65 plates will fit upon said tie body and said bolts will be reinforced.

In testimony whereof I hereunto affix my signature in presence of two witnesses.

DANIEL I. COWGILL.
